PRODUCTION OF MOTOR FUEL

Harold V. Atwell, White Plains, N. Y., assignor to
Process Management Company, Inc., New York,
N. Y., a corporation of Delaware

Application December 14, 1935, Serial No. 54,417

1 Claim. (Cl. 196—10)

My invention relates to the production of low-boiling hydrocarbon oils suitable for use as motor fuel and having high anti-detonating properties from relatively high-boiling hydrocarbon oils by a combination of pyrolytic decomposition and polymerization steps.

In cracking oil for the manufacture of gasoline, the products ordinarily include, in addition to gasoline, various other types of hydrocarbons, both heavier and lighter than gasoline. The customary procedure is to fractionally separate these products in the order of decreasing boiling points. Thus the cracked products are first separated into vaporous and residual products or tars, which are either converted into coke or removed from the system as fuel oil, it being ordinarily impracticable to attempt to crack these heavy materials to gasoline on account of the fact that they decompose too readily to carbon and because of the relatively poor yield of gasoline produced thereby. The separated vaporous products are then fractionated to recover relatively high-boiling but non-residual distillation products which are ordinarily designated "gas oils" and which may include products boiling over a fairly wide range, for example, from around 400° F. to 700° F. or more, depending somewhat upon the end-point of the gasoline fraction and other factors. This gas oil, being free from residual constituents, forms a good cracking stock and may be recycled for further cracking to produce gasoline, especially since in many instances it consists in part of virgin constituents distilled from un-cracked or crude oil charged into the system at a point beyond the actual cracking zone. However, the lighter constituents in the "gas oil" range are relatively much more refractory than the heavier constituents and, consequently, when it is attempted to recycle the entire gas oil cut lying between residual oil or tar on the one hand and gasoline on the other hand, the cracking conditions must of necessity constitute a compromise between conditions most desirable for the conversion of the heavier constituents of this fraction and conditions most desirable for the conversion of the lighter constituents of this fraction, and, consequently, neither group of constituents is cracked under optimum conditions.

After the separation of the products having higher boiling points than gasoline, the remaining vapors are separated into a condensable or gasoline fraction and a gas fraction consisting partly of hydrogen and methane, which are relatively inert materials. In addition to hydrogen and methane, however, there are present various

paraffinic and olefinic gases, such as ethane, ethylene, propane, propylene, butanes and butylenes, which may be regarded as more or less intermediate between the fixed gases and the true gasoline fraction. A certain amount of these normally gaseous materials may be included in the gasoline fraction but under present day conditions there is normally an excess of these materials. As a result of this, depending upon the conditions and particularly the pressure under which condensation is effected, these intermediates may either be included in the gas drawn from the gas separator or separately recovered in the stabilization of the gasoline. In any event, these light intermediate materials, especially when free or relatively free from hydrogen and methane, may be polymerized to normally liquid low-boiling hydrocarbon oils suitable for use as motor fuel and having exceptionally high anti-detonating properties, by subjecting them to suitably elevated temperatures and pressures, with or without catalysis.

While it has thus been suggested to effect the polymerization of the gases liberated in the ordinary course of cracking, little attention has been paid to the possibility of employing polymerization as a means of obtaining a further additional yield of gasoline of high quality from an oil cracking unit over and above that obtainable by simply polymerizing the cracked gases normally produced.

My invention, therefore, has for an object the provision of a method whereby the products obtained in an oil cracking operation may be converted to a higher degree than has heretofore been possible to motor fuel products of exceptionally good character, without overburdening the primary oil cracking operation, together with such additional operative advantages and improvements as may hereinafter be found to obtain.

My invention contemplates cracking a hydrocarbon oil under the usual conditions with recycling of the heavier clean distillation products, and with the segregation of the heavy residual products or tars as well as a refractory distillate lighter than the recycle stock and which will hereinafter be designated for convenience as a "light gas oil." According to my invention, this light gas oil fraction is then subjected to a very high temperature in order to drastically crack the same and effect its conversion in large measure to gaseous products of a highly olefinic character. The highly heated products are then commingled with the residual oil or tar referred to hereinabove in order to accomplish a conversion of the latter

- to coke or very heavy residuum and lighter products including a considerable amount of normally gaseous constituents. The gases obtained in this operation are then subjected to gas polymerization either with or without previous fractionation as desired. While gasoline may be produced in this type of operation, no attempt is made to obtain an especially high yield of gasoline, the object being rather to produce as much gas as possible.
- 5 10 Any higher-boiling oils may be converted into coke or recycled in the cracking operation.

As has been mentioned, the polymerization of the gas may be effected either by heat and pressure alone, or by means of a catalyst under more moderate conditions of temperature and pressure, and the gases derived from the initial oil cracking operation may be combined with those obtained by cracking the light gas oil and residual oil before being subjected to polymerization. In any event, the polymerization is so conducted as to obtain a low-boiling motor fuel product having high anti-detonating properties while any higher-boiling polymers may be returned advantageously to the primary oil cracking operation for further conversion.

In order that my invention may be fully set forth and understood, I now describe, with reference to the drawing accompanying and forming part of this specification, a preferred form and manner in which my invention may be practiced and embodied. In this drawing, the single figure is a more or less diagrammatic elevational view of apparatus for effecting conversion of hydrocarbons in accordance with my invention.

35 Referring to the drawing, a suitable hydrocarbon oil charging stock, such as a reduced crude or a gas oil, is introduced by means of a pump 1 and a line 2 into an evaporator 3 receiving hot cracked products from an oil cracking furnace 4. In a preferred instance, the evaporator 3 is maintained under a pressure of about 200 lbs. per sq. in. (although higher or lower pressures may be used) and under such temperature as to retain as liquids heavy residual constituents unsuitable for further cracking to gasoline in the ordinary manner, while permitting distillable constituents to pass overhead in vapor form into a fractionating column 5, where distillate higher boiling than the desired motor fuel fraction is condensed and separated. The charging stock, especially where it consists of gas oil, may be introduced above the tray 6 if desired. A higher boiling distillate or heavy gas oil fraction is removed from the bottom of the fractionating column 5 by means of a trap-out tray 6 and is delivered by means of a line 7 and a pump 8 to the oil cracking furnace 4, where it is subjected to conversion conditions of temperature and pressure, for example, a temperature of from 950° to 1050° F., under a pressure of from 300 to 1,000 lbs. per sq. in. The hot products from the oil cracking furnace 4 then pass through a transfer line 9 having a pressure-reducing valve 10 into the evaporator 3.

65 The oil collected in the bottom of the evaporator 3, especially where the evaporator 3 is maintained under a pressure of, for example, about 200 lbs. per sq. in. or more, will ordinarily contain some distillable constituents and, in order to recover these, the heavy oil from the bottom of the evaporator 3 is delivered through a line 12 having a pressure-reducing valve 13 to a tar flasher 14, which may be maintained under a reduced pressure of, for example, from atmospheric pressure to 50 lbs. per sq. in. The distillate separated in the tar flasher 14 passes in vapor

form through a line 15 to a condenser 16 and separator 17, from which this distillate may be withdrawn through a line 18 having a valve 19 and a pump 20 and returned to the fractionating column 5. The flashed residual oil or tar is removed from the bottom of the tar flasher through a line 21 having a valve 22.

5 10 Overhead vapors from the bubble tower 5 and comprising gasoline, fixed gases and intermediate gases or vapors, pass through a vapor line 25 to 10 a condenser 26 and thence to a gas separator 27 from which fixed gases may be withdrawn through a valved line 28 while the separated gasoline is withdrawn through a line 29, which may be provided with a pump 30, and delivered to a stabilizer 31. The stabilizer 31 may be of the usual type, stabilized gasoline being withdrawn from the bottom of the stabilizer through a valved line 32 while overhead products pass through a line 33 to a condenser 34 and receiver 35. The stabilizer 31 will ordinarily be operated under several hundred pounds pressure and, under these conditions, the products recovered from the receiver 35 will ordinarily comprise liquefied gases of paraffinic and olefinic character, largely free from hydrogen and methane and suitable for gas polymerization. These products are withdrawn from the receiver 35 through a line 36 having a pump 37 and a portion of these products may be returned through a valved line 38 to the stabilizer 31 as reflux. Any gases or vapors which separate in gaseous form at this point may be withdrawn from the receiver 35 through a valved line 39.

30 35 In accordance with my invention, a portion of the gas oil condensate condensed in the fractionating column 5, and preferably comprising a lighter and more refractory fraction than that withdrawn from the trap-out tray 6, is withdrawn as a side stream from a trap-out tray 41 located at an intermediate point in the fractionating column 5. This fraction then passes through a line 42 to a pump 43 and is then delivered by means of a line 44 to a second oil cracking furnace 45, where it is subjected to very drastic cracking conditions with the object of converting it largely to gases or, at any rate, to obtain a relatively high yield of gas and without any especial attempt to obtain a high gasoline yield per se. For this purpose, the light gas oil fraction may be subjected to a temperature of 40 from 1100° to 1300° F. under a relatively low pressure ordinarily in excess of 50 lbs. per sq. in. but preferably not exceeding 500 lbs. per sq. in., and with a sufficient rate of flow through the furnace to prevent deposition of carbon therein. The 45 highly heated cracked products then pass through a transfer line 46 into a reaction chamber or coking drum 47. Tar or residual oil withdrawn from the tar flasher 14 through the line 21 is also delivered by means of a pump 48 and a line 49 to the chamber 47. In the preferred instance illustrated, the line 49 may communicate with the transfer line 46 between the furnace 45 and the chamber 47 but it will be obvious to those skilled in the art that the tar or 50 residual oil may be delivered directly to the chamber 47 if desired. In the chamber 47 the tar is sufficiently heated by the cracked products from the furnace 45 to effect a cracking thereof largely to gaseous products and coke. The coke may be 55 removed from the bottom of the chamber 47, of which a number may be provided in the usual manner in order to permit intermittent removal of coke without shutting down the entire operation. It is preferred to maintain a temperature 60

of from 900° to 1100° F. in the chamber 47 and if the heat of the cracked products from the furnace 45 proves insufficient for this purpose the tar from the tar flasher 14 may be independently heated by any suitable means (not shown on the drawing) before being brought into contact with the hot products from the furnace 45. The temperature of such independent heating may be as high as possible without undue deposition of carbon from this heavy and dirty stock, for example to about 750°-50° F. The vaporous products from the chamber 47 then pass through a line 51 to a fractionating column 52 where they are fractionated in the usual manner to remove products heavier than gasoline. Relatively heavy products of this character containing dirty residual constituents carried out of the chamber 47 are withdrawn from the bottom of the fractionating column 52 through a line 53 having a valve 54 and a pump 55 and may be returned through a line 56 to the chamber 47, the line 56 either communicating with the transfer line 46 as shown or leading directly to the chamber 47. Clean condensate or gas oil may be withdrawn as a side stream from a trap-out tray 60 located as shown in the fractionating column 52 and recycled by means of a line 61 having a valve 62 and a pump 63 to the inlet of the oil-cracking furnace 45 through a line 63'.

Overhead vapors comprising gasoline and lighter products pass from the top of the fractionating column 52 through a line 64 to a condenser 65 and thence to a separator 66 from which any gasoline may be withdrawn through a valved line 67. Due to the relatively low pressure at which condensation is effected in this type of operation the intermediate gases lying between methane on the one hand and gasoline on the other hand are ordinarily separated in gaseous form at this point and may be withdrawn from the separator 66 together with hydrogen and methane and delivered through a valved line 70 having a pump 71 to a suitable gas fractionating unit 72 where they are separated into two fractions, one comprising largely hydrogen and methane and the other comprising largely ethane, ethylene, propane, propylene, butanes and butylenes. The details of the gas fractionating unit 72 have not been illustrated, as units for this purpose are well known in the art and since my invention is not concerned with the manner of fractionation.

The hydrogen and methane fraction is withdrawn from the gas fractionating unit through a valved line 73 while the fractionated paraffinic and olefinic gases pass through lines 74 and 75 to a pump or compressor 76 and thence through a line 77 to a gas polymerizing furnace 78. In passing through the furnace 78, the gases are subjected to a suitable elevated temperature and pressure and for a sufficient time to effect the desired degree of polymerization to low-boiling normally liquid products. Where catalysts are not employed, or where the effect of such catalysts as may be present is secondary, the temperature and pressure employed at this point are preferably from 750° to 1050° F. and 500 to 3,000 lbs. per sq. in., although higher temperatures and lower pressures may be employed where products of a more highly aromatic character are desired. Where highly effective catalysts are employed, the temperatures and pressures may be considerably lower; thus, for example, when using phosphoric acid type catalysts and other catalysts of about the same degree of effectiveness, tempera-

tures of from 300° to 700° F. and pressures of from 200 to 1,000 lbs. per sq. in. may be utilized. In the preferred instance in which the conversion is effected by means of heat and pressure, as distinguished from catalysis, the products pass from the gas polymerizing furnace 78 to a soaking coil 79 and thence through a cooling device 80 into a high pressure separator 81 from which gases may be withdrawn through a valved line 82 while liquid products pass through a line 83 having a pressure-reducing valve 84 into a fractionating column 85 of conventional construction.

In the fractionating column 85, the fractionation is so carried out as to pass overhead all gasoline-like materials and lower-boiling products while condensing and separating polymers having boiling points too high to warrant their inclusion in the motor-fuel product. These high-boiling polymers are withdrawn from the bottom of the fractionating column 85 through a line 86 having a valve 87 and may be delivered by means of a pump 88 and line 89 to the inlet of the oil cracking furnace 4 for further conversion. Alternatively, this material may be diverted from the system for any desired purpose.

The overhead products from the fractionating column 85 pass through a vapor line 91 to a condenser 92 and thence to a separator 93 from which polymerized gasoline is withdrawn through a valved line 94, while overhead products comprising largely constituents lying between methane on the one hand and gasoline on the other hand are removed through a valved line 96 and are returned through the line 75 to the pump or compressor 76 and thence into the furnace 78. Where catalysts are employed, such recycling may sometimes be dispensed with.

Where the original charging stock consists of a distillate, such as gas oil, the oil in the evaporator 3 may contain a considerable amount of refractory products of cracking but more suitable for cracking to gas than to gasoline. Where this is true, such constituents may be segregated from the heavier residual constituents and delivered to the furnace 45. For example, in the instance shown in which bottoms from the evaporator 3 are flashed in the tar flasher 14, the flashed distillate recovered at 17 or any desired portion thereof may be delivered to the furnace 45 through a line 100 having a pump 101 and a valve 102, for cracking in the manner set forth hereinabove with reference to the light gas oil withdrawn from the trap-out tray 41.

Those products of the initial oil cracking operation which are lighter than gasoline and suitable for polymerization can be delivered to the gas polymerizing furnace 78. In the preferred instance illustrated, the excess material recovered from the separator 35 over and above that required for refluxing to the stabilizer 31 is delivered from the pump 37 through a line 97 having a valve 98 and communicating with the line 75 whereby these products are delivered to the pump or compressor 76 and thence to the gas polymerizing furnace 78.

It will likewise be obvious that the gases from the separators 27, 35 and 81, which are withdrawn therefrom through the lines 28, 39 and 82, respectively, may likewise be delivered to the gas polymerizing furnace 78. Preferably, however, these gases and particularly those withdrawn from the separators 27 and 81, if returned at all, are not entirely returned due to their content of hydrogen and methane but are preferably first delivered to the gas fractionating

unit 72 for removal of hydrogen and methane, the remaining fractionated gases being delivered through the unit 72 to the lines 74, 78 and 77 in the manner described hereinabove.

- 5 It will be obvious in any event that my invention is not limited to the details of the specific fractionating methods employed in connection with any of the three conversion units, the light products of each of these units being fractionated 10 in any suitable manner to separate a gasoline fraction, a hydrogen and methane fraction and an intermediate fraction consisting primarily of polymerizable gases free from hydrogen and methane, the gasoline fractions being withdrawn 15 for use, the hydrogen and methane fraction being discarded from the system and the intermediate fractions being delivered or recycled as the case may be to the gas polymerizing furnace 78.

It will likewise be obvious to those skilled in the 20 art that the details of the oil cracking operation may be considerably varied in accordance with the requirements of the original charging stock and the particular type of process employed and that in some cases the tar or residual oil withdrawn 25 from the primary evaporator 3 may be delivered directly to contact with the hot products from the cracking furnace 45 without first being passed to the tar flasher 14. However, the tar flasher 14 is useful in effecting the segregation of 30 materials which may be advantageously recycled in the cracking operation and residual materials which may more advantageously be delivered to the more drastic cracking operation conducted primarily for the purpose of making polymerizable 35 gas.

It will be clear from the above that my invention makes it possible to carry out an oil conversion operation in an advantageous manner since those products which are suitable for cracking to 40 gasoline in the usual manner are segregated as such and cracked for the production of gasoline under optimum conditions, while products less suitable for cracking on account of their residual or refractory character, as the case may be, are 45 segregated as formed from the oil cracking operation and are advantageously converted into gaseous products capable of being polymerized to produce a motor fuel of exceptionally high character. As a matter of fact, the gasoline produced in each of the three conversion operations 50 is of exceptionally good character and any two or all three of these gasoline products may be blended in any desired proportions to produce a

blended motor fuel product of exceptionally good quality.

It will further be obvious to those skilled in the art that while I have described my invention hereinabove with reference to various preferred 5 details of operation, my invention is not limited to such illustrative details but may variously be practiced and embodied within the scope of the claim hereinafter made.

I claim:

A process of manufacturing low boiling hydrocarbon oil suitable for use as motor fuel which comprises subjecting a relatively heavy hydrocarbon oil to an elevated temperature to crack the heavy oil to higher and lower boiling products, 15 separating heavy residual oil unsuitable for recycling from the cracked products, fractionating the remaining cracked products to recover a heavy gas oil suitable for recycling, a distillate fraction comprising a light refractory gas oil, a 20 cracked gasoline fraction, a fixed gas fraction consisting largely of hydrogen and methane, and a fraction intermediate the gasoline fraction and the fixed gas fraction, recycling the last mentioned heavy gas oil to the first cracking step, separately subjecting the distillate fraction to a 25 temperature of about 1100° F. to 1300° F. to crack the distillate fraction to produce primarily olefinic gas without regard to producing an optimum 30 yield of motor fuel, commingling the high temperature highly cracked products from the last mentioned high temperature cracking step with the first mentioned heavy residual oil to crack the heavy residual oil largely to coke and gaseous 35 products, fractionating the gaseous products to 40 separate all material higher boiling than gasoline to heavy and light fractions, a gasoline fraction and gases containing olefins, returning the light fraction to the high temperature cracking step and commingling the heavy fraction with the high temperature highly cracked products from the high temperature cracking step, combining the last mentioned gases containing olefins with the fraction intermediate the gasoline fraction and the fixed gas fraction and subjecting the mixture 45 of gases to an elevated temperature to effect the polymerization of the constituents thereof to normally liquid low boiling oil, recovering a gasoline-like fraction and a heavier fraction from the products of polymerization and returning at least a part of the heavier fraction to the first cracking step for further conversion.

HAROLD V. ATWELL.
